UNITED STATES PATENT OFFICE.

LEWIS KELLY, OF SARANAC, MICHIGAN.

COMBINED IRONING-BOARD AND CABINET.

1,174,587.

Specification of Letters Patent.

Patented Mar. 7, 1916.

Application filed January 21, 1915. Serial No. 3,549.

To all whom it may concern.

Be it known that I, LEWIS KELLY, a citizen of the United States, residing at Saranac, in the county of Ionia and State of Michigan, have invented certain new and useful Improvements in Combined Ironing-Boards and Cabinets; and I do declare the following to be a full, clear, and exact description of the invention, such as will enable others skilled in the art to which it appertains to make and use the same.

This invention relates to improvements in combined ironing boards and cabinets.

The object of the invention is to provide a highly ornamental and useful piece of furniture combining therein an ironing board casing, a table and a cabinet for medicines, toilet or other articles.

Another object is to provide simple and efficient means for guiding and supporting an ironing board during its insertion into and removal from the cabinet.

Another object is to provide a sleeve board and means for detachably mounting it on the ironing board.

Another object is to provide an improved clothes rack foldable in and constituting a part of the cabinet.

With these and other objects in view, the invention consists of certain novel features of construction, and the combination and arrangement of parts as will be more fully described and claimed.

In the accompanying drawings, Figure 1 represents a front elevation of a cabinet constructed in accordance with this invention and shown in closed position; Fig. 2 is a similar view with the doors of the cabinet shown open and the ironing board enhouised in operative position; Fig. 3 is a vertical section taken on the line 3—3 of Fig. 2 showing the ironing board in open operative position; Fig. 4 is a horizontal section taken on the line 4—4 of Fig. 2; Fig. 5 is a detail vertical section taken on the line 5—5 of Fig. 3.

In the embodiment illustrated, a cabinet 1 is shown which may be of any desired size and composed of any suitable or desired material, it being preferably about six feet high and three feet wide and of any desired depth to adapt it to accommodate an ironing board of ordinary size. This cabinet comprises an upright ironing board receiving

chamber 2 extending substantially the length of the cabinet and having a cross

bar 3 extending transversely across the front thereof intermediately of its ends. On each side of the chamber 2 above the cross bar 3 thereof, are disposed closets or chambers 4 and 5 each having a hinged closure and provided at their lower ends with drawers 6 and 7 which may be used for any purposes desired.

As shown, a rack 8 is disposed longitudinally on the outer face of the casing 1 near its lower end, and which is designed to adjustably support a leg on the ironing board as will be hereinafter more fully described. A door 9 is hingedly connected at its upper end to the cross bar 3 of the casing and it may be secured at its lower end to the casing by any suitable fastening means. A foldable bail 10 is pivotally mounted at its opposite ends on the inner face of the casing at opposite sides thereof and the cross bar 11 of said bail is designed to engage a hook 12 on the inner face of the door 9 when the door is in horizontal position to adapt it to perform the function of a table. When this bail is disengaged from the door to permit the closing of the latter it will be swung into the casing out of the way.

The upper portion of the central chamber 2 of the casing 1 is closed by a hinged door 13, which is preferably provided with a mirror although this is not an essential feature. Disposed in the door 13 below the mirror is a hinged receptacle 14, especially designed for containing combs or similar articles, and it is pivotally mounted at its lower edge in an opening in the door being adapted to swing outwardly to afford access thereto and inwardly flush with the outer face of the door when not in use. Longitudinally slotted metal straps 15 and 16 are secured to the top of the cabinet extending transversely thereof with adjusting screws 17 passing through the slots in said straps to adapt the latter to be adjustably mounted transversely on the casing top. These straps are provided at their rear ends with upwardly projecting lateral ears 18 which are apertured to receive fastening members for connecting the straps to the wall or other suitable support and thereby securely hold the cabinet in upright position.

L-shaped straps or angle-irons 19 are also preferably secured to the lower end of the cabinet at the front thereof and their laterally extending feet 20 are slotted to receive fastening elements for adjustably se-

curing them to the floor, which is desirable in the event that the washboard or chair board or the wall projects beyond the face thereof.

- 5 Guides 21 and 22 are formed on the inner faces of the opposite sides of the casing chamber 2 extending from a point above the cross bar 3 to a point near the lower end thereof and as shown, these guides are 10 made in the form of longitudinally extending grooves disposed in transverse alignment and which are designed to receive projections on the opposite sides of the ironing board to be described.
- 15 An ironing board 25 shaped in the usual manner with one end straight and the other end rounded is shown of a width slightly less than the width of the chamber 2 and of a length slightly less than the length of 20 said casing in which it is designed to be housed when not in use. This ironing board 25 is provided at its straight rear end on its lower face with a transversely extending cleat 26, the ends of which project beyond the side edges of the board and 25 are designed to be mounted in the guides 21 and 22 of the casing for slidably supporting the rear end of the board in said casing and permitting it to be moved longitudinally in said casing for inserting and 30 withdrawing it as will be hereinafter more fully described.

A cleat 27 extends transversely across the upper face of the rear ends of the board 25 and terminates at its opposite ends flush with the side edges of the board. A shaft 35 in the form of a wire bail 28 is pivotally mounted on the cleat 27, and as shown is in the form of a substantially rectangular loop having one side thereof open and provided with laterally extending arms 29 which are adapted to be mounted on the cleat 27 and pivotally secured thereto by means of eye-bolts 30 which also extend 40 through the ironing board and the cleat 26 on the lower face of the ironing board, as is shown clearly in Fig. 5. The ends of the arms 29 as shown project beyond the side edges of the board 25 and are also designed 45 to engage the guides 21 and 22. The U-shaped member 28 is adapted to be folded flat against the front of the ironing board when not in use, it being designed to support one end of a sleeve board when in operative position as will be hereinafter more 50 fully described.

Stop blocks 31 and 32 are adjustably mounted in the upper ends of the guides 21 and 22 to limit the upward movement of 55 the rear end of the ironing board when it is pulled upwardly and swung outwardly into horizontal operative position, the projecting ends of the cleat 26 engaging said stops when the board is in its extreme upward position and thus holds it in hori-

zontal position ready for use. These stops are adjustable to adapt the board to be supported at the desired height for use by shorter or taller persons.

Disposed on the rear wall of the chamber 70 2 at opposite sides thereof are two rack bars 33 and 34 disposed longitudinally of the chamber 2 and extending above and below the space occupied by the cross bar 3, and which are designed to be adjustably 75 engaged by the projecting rear edge of the cleat 26, for supporting the rear end of the ironing board 25 when in horizontal position as is shown clearly in Fig. 3.

A leg 35 is hinged at one end to the lower 80 face of the ironing board 25 at a point intermediately of its ends preferably nearer the rear end thereof, and the free end of this leg is designed to engage the rack 8 on the lower portion of the outer face of the casing 85 whereby the front end of the board is reliably supported in horizontal position.

A catch or pivoted button 36 is mounted on the rear wall of the chamber 2 near its outer end and is designed to engage the rounded outer end of the ironing board when it is disposed within the casing and securely holds said board against outward movement. A similar button 37 is mounted on the lower face of the front end of the 95 ironing board for holding the hinged leg 35 in folded position.

A sleeve board 38 is designed to be detachably mounted on the ironing board 25 when desired and as shown this board is 100 made about one-half the length of the ironing board proper and is provided at its rear end on its opposite side edges with notches 39 which are adapted to engage the end members of the U-shaped loop of the bail 28 105 when it is opened into the position shown in Fig. 3 when said sleeve board is to be used and which reliably supports said board at its rear end and prevents upward and lateral movement thereof. This sleeve board 38 has an aperture 40 formed in its rear end and in which is pivotally mounted a supporting leg 41 which may be swung outwardly on either side of the sleeve board and is designed to form a spacing member or support for the board when in operative position on the ironing board, it being obvious that the free end of said leg will engage the upper face of the ironing board when in this position. This leg 41 is made of a length 110 sufficient to adapt it to be housed within the opening 40 when not in use so that it will not project on either side of the sleeve board when folded into said opening, and yet it may be swung outwardly on either side 115 thereof in the manner above described, said leg being pivoted near one end of the opening and its pivoted inner end being adapted to engage the end wall of the opening to hold it in open position. A cleat 42 is 120

130

mounted longitudinally on one face of the sleeve board 38 and is preferably rounded at its opposite edges, being designed for use for pressing seams and which is disposed on the lower face of the board when it is used for ironing sleeves. From the above it will be obvious that this sleeve board may be reversed when desired and used either as a sleeve board or as a seam presser. When not in use, this sleeve board is disengaged from the ironing board by turning the bail member 28 downward and disengaging the end of said sleeve board therefrom and the leg 41 of said board is then folded into the opening therein and the board may be hung on the rear wall of the chamber 2 and be disposed behind the ironing board 25 when the latter is closed within the casing.

When the parts are in the position shown in Fig. 1 with the ironing board housed within the casing and it is desired to use said board, the door 13 is first opened and the loop or button 36 turned to disengage it from the free end of the board 25 and said board is then moved forwardly whereby its lower end moves upwardly in the guides 21 and 22 until the projecting ends of the cleat 26 thereof engages the stop blocks 31 and 32 at the upper ends of said guides and the board will then be swung outwardly into horizontal position. The leg 35 is then swung downwardly and the free end thereof engaged with the rack bar 8 on the lower end of the casing in which position the board will be ready for use, the rear projecting edge of the cleat 26 thereof being first engaged with the racks 33 and 34 on the rear wall of the chamber 2, which reliably support the rear end of the board and prevents it from moving upwardly or downwardly when in use.

When it is desired to use the sleeve board 38 either for ironing sleeves or for pressing seams, the bail 28 is swung upwardly and said sleeve board 38 is moved from the wall of the chamber 2 and after swinging the leg 41 thereof into the desired position according to the side of the board which is desired to be used, said leg is engaged with the upper face of the ironing board 25 and the rear end of said board 38 is inserted in the bail 28 with the notches 39 thereof engaging the opposite ends of said bail and said sleeve board will then be ready for use.

After the board has been used and it is desired to replace it in the cabinet, the sleeve board is removed in the manner above described and hung on a suitable nail or other element within the chamber 2. The bail 28 is then folded down flat against the upper face of the board 25 and said board is swung upwardly and moved downwardly, being guided in this movement by the engagement of the ends of the cleat 26 with the guides 21 and 22, and this movement continues un-

til the straight inner or rear end of the ironing board contacts with the lower end of the chamber 2. The rounded front end thereof is then secured in inoperative position by engaging the button 36 therewith and then the leg 35 is folded and secured by means of the button 37. The door 13 is then closed and the cabinet will present a neat and attractive appearance without any visible signs of the ironing board.

When it is desired to obtain the use of a table, the lower end of the door 9 is released and it is swung upwardly on the hinges at the upper end thereof until it reaches a horizontal position, when the bail 10 mounted on the casing will be swung outwardly and the cross bar 11 thereof engaged with the hook 12 on the inner face of said door which will then be ready for use as a table.

The upper end of the casing 1 is preferably provided with two vertically spaced horizontally disposed top members 43 and 44, forming a chamber 45 between them which is closed at one end and at the rear for a portion of its length, and open at its front and the other end, and which is designed to receive a foldable clothes rack 46 when in inoperative position. This rack comprises two vertically spaced supporting members here shown in the form of right angular plates 47 and 48 connected along the straight edges thereof and having curved front ends, and between which are pivotally mounted a plurality of supporting bars or rods 49, which are adapted to be swung outwardly when desired for supporting clothes or other articles. The supporting casing for these rods, is pivotally mounted as shown at 50 at its angle, on the rear corner of the open upper end of the cabinet and which when swung into closed position forms a closure for said open end and for the open portion of the rear side thereof as shown in Fig. 4.

When in folded position and swung into the chamber 45 the uppermost portion of the folding bar 49 constitutes a closure for the open front end of the chamber 45 and it may be held in closed position by a suitable button 51 mounted on the front edge of the cabinet 1.

I claim as my invention:—

1. An ironing cabinet comprising a closed casing, a rack extending longitudinally of said casing on the rear wall thereof, longitudinal grooves formed on the inner faces of the opposite sides of said casing and spaced from the rear wall thereof, an additional rack disposed longitudinally on the outer face of the front wall of said casing at its lower end, an ironing board mounted in said casing and being provided with projections, the latter being secured to the upper face of said board near its rear end and

extending laterally from the opposite sides thereof for sliding engagement in said grooves; a cleat secured to the lower face of said board and projecting beyond the rear edge thereof, said cleat engaging the first mentioned rack when the board is raised to horizontal position, a leg hinged at its upper end to the lower face of said board and provided at its other end for engagement with 10 said additional rack for supporting the front end of the board, substantially as set forth.

2. An ironing cabinet comprising a closed casing, a pair of rack bars disposed longitudinally of said casing and secured to the 15 rear wall thereof at its opposite sides, transversely aligned longitudinal grooves formed on the inner faces of the opposite sides of said casing, said grooves being spaced forwardly from said rack bars and extending 20 from a point above the latter to a point near the lower end of said casing, an additional rack bar disposed longitudinally on the outer face of the front wall of said casing at its lower end, an ironing board mounted 25 in said casing, a cleat extending transversely across the upper face of the rear end of said board, the ends and rear side edge of said cleat being flush with the side edges and rear

edge respectively of said board, a shaft extending longitudinally across the upper face 30 of said cleat, the ends of said shaft projecting beyond the ends of the latter for sliding engagement in said grooves, an additional cleat extending transversely across the lower face of said board beneath the aforementioned cleat, the rear edge of said additional cleat projecting beyond the rear edge of said board for engagement with said pair of rack bars when the board is raised to horizontal position, eye bolts extending through said 35 cleats and said board for securing them together and for securing said shaft to the first-named cleat, a leg hinged at its upper end to the lower face of said board and provided at its other end for engagement with said additional rack bar for supporting the front end of the board, substantially as set forth.

In testimony whereof I have hereunto set my hand in presence of two subscribing witnesses.

LEWIS KELLY.
